US00D823492S

(12) **United States Design Patent** (10) Patent No.: **US D823,492 S**
(45) Date of Patent: **** Jul. 17, 2018**

(54) **LIGHT EMITTING DEVICE**(71) Applicant: **Cree, Inc.**, Durham, NC (US)(72) Inventors: **Erin R. F. Welch**, Chapel Hill, NC (US); **Colin Kelly Blakely**, Franklinton, NC (US)(73) Assignee: **Cree, Inc.**, Durham, NC (US)(**) Term: **15 Years**(21) Appl. No.: **29/579,906**(22) Filed: **Oct. 4, 2016**(51) LOC (11) Cl. **26-04**
